(54) **BLEACHING BEES WAX YELLOW**

(76) Inventor: **John N. Schultze**

John A. Shultz of New York City
Letters Patent

The Schedule referred to in these Letters Patent and making part of the same, containing a description in the words of the said John A. Shultz himself, of his improvement in the mode of bleaching yellow bees wax.

To all persons to whom these presents shall come, I John A. Shultz of the City of New York Chemist and Greeting. Be it known that I the said John A. Shultz, have invented, made and applied to use a new, useful improvement in the mode of bleaching yellow bees wax, in such a manner as to render the same of a beautiful white colour fit for burning and other purposes to which white wax is usually applied to wicks. I give the name of alabaster wax.

The process of bleaching may be commercially performed as follows. Prepare the vats of oak boards, and nearly equal in size, and placed adjacent to each other, their dimensions about four feet long three feet wide and three feet deep, to be numbered 1, 2, 3, & 4.

Into the vat No 1. put 125 gallons cold water and add to this 200 lbs oxy muriate of lime of best quality (oxy muriate of black or soda have been applied for the same purpose with equal success, but owing to their expense being too high have not recently been used.) Agitate this mixture with a wooden paddle for about one quarter of an hour then suffer the excess of lime to settle.

Into vat No 2. place five hundred pounds of good yellow bees wax. By an application of steam this wax is melted (instead of steam direct application of fuel will answer the same purpose) when melted the steam withdrawn from this vat and the impurities of the wax separated to settle for half an hour. Into vat No 3 pour this wax from its deposit, by applying steam and continued stirring the above described solution of oxy muriate of lime is added at intervals so as to keep the wax in a liquid state, by this operation the wax assuming a white appearance the quantity of the solution of oxy muriate of lime used in the first process

depends on the quantity of coloring matter in the wax, but generally nearly all the clear solution is applied. Should the quantity of the solution added be in excess of the coloring matter in the wax an aperient acid taste on the tongue will be perceived, otherwise a saline taste.

This operation under continued stirring, and heat by steam is ended within one hour then add 20^{oz} concentrated sulphuric acid ^{sp. gr. 1.8} only diluted with 30^{oz} of cold water all other acids can be used with equal success, but they are too expensive. By this addition and continued agitation for half an hour the caustic lime and water &c which are united with the wax are separated from it, and the wax is separated from the water &c, floats on the surface. The steam is now withdrawn, and the water sulphate of lime &c in half an hour settles to the bottom of the vat.

Should the wax not be of sufficient whiteness after the water and sulphate of lime are separated, the operation is repeated, but previously in vat No 1. nearly five gallons of water must be again poured and well strained, and the lime allowed to deposit. It is seldom that one process renders the wax sufficiently white and I have therefore to repeat the operation, and even sometimes a third time.

When sufficiently white, say after the second operation and after one hour settling pour the white wax which yet contains some water &c, into vat No 4. which is also heated by steam, being careful to take as little of the settled water as possible. When this is done add 30^{oz} of coarse salt (muriate of soda or any other salt or substance which is soluble in water & which renders it specifically heavier) but for convenience I have taken muriate of soda) this salt has no action on the wax but becomes soluble in the water, and separates it from the wax by settling below the wax, where the liquid wax requires a clear transparent appearance; though by continued stirring, withdraw the steam and suffer it to settle for one hour then pour the wax carefully from the salt water in such vessels as you may wish for cooling.

In order to give this wax a clear white appearance I have added in vat No 4. previous to its being poured out one oz. powdered

Antwerp blue previously mixed with one quart. of this melted wax.
N. B. Should the oxyurinate of lime in vat No 3. burn except by the addition of Sulphuric acid a very offensive smell will ensue for about ten minutes, which is also unhealthy, being oxyurinistic Gas, & therefore care should be taken not to inhale it.

The heat applied to wax in this process, should not at any time exceed 100 degrees - The size & figure of the rats may of course be varied according to the quantity of wax to be whitened and application of heat may be direct to the material instead of by steam. I do testimony that the above is a true specification of my said improvement as above described. I have hereunto set my hand this 13th day of April in the year of our Lord one thousand eight hundred and thirty two.

Witness,

Elisha H. Wilder

A. Silliman

John A. Muller.

(Patented 30 April 1832.)
